BAG HOLDER

John C. Broome, Dunedin, Fla., assignor to Food Machinery Corporation, San Jose, Calif., a corporation of Delaware

Application July 5, 1943, Serial No. 493,603

10 Claims. (Cl. 248—100)

My invention relates to devices for holding bags while filling these.

The invention aims, for its objects, to provide a bag holder that is inexpensive to build, one which is simple in operation, one which may be rapidly disengaged from the bag when the latter has been filled, one which operates with ease and rapidity to engage a bag in preparation for filling the latter; and a bag holder which holds a bag with the mouth thereof positively expanded during a filling operation.

The manner of accomplishing the foregoing objects, as well as further objects and advantages, will be made manifest in the following description taken in connection with the accompanying drawing, in which:

Fig. 1 is a perspective view of a preferred embodiment of the bag holder of my invention mounted upon a stationary support.

Fig. 2 is a horizontal sectional view taken on the line 2—2 of Fig. 1.

Fig. 3 is an enlarged vertical sectional view taken on the line 3—3 of Fig. 1.

Referring specifically to the drawing, I have shown my invention therein as embodied in a bag holder 10 which is mounted upon arms 11 provided on a fixed pedestal 12. This bag holder is frequently mounted on a bagging and weighing device. It is here shown as having a stationary mounting to simplify the disclosure as the mounting is not necessarily a part of the invention.

The bag holder 10 includes an annulus 15 having a base section 16 and two pairs of auxiliary sections 17. The base section 16 is secured as by welding to the arms 11 in order to support the annulus 15 and has a bead 20 extending outwardly therefrom adjacent its lower edge for assisting in supporting a bag B on the holder 10. There are preferably two auxiliary sections 17 in each of the two groups of these aforesaid and the sections of each group are joined together and one edge of one of said sections of each of said groups is connected to a corresponding edge of the base section 16 by internal hinges 21 the axes of which are disposed within the annulus 15 and preferably substantially parallel with the axis of this annulus. The hinges 21 are also applied so as not to permit further outward swinging of one of the sections 16 or 17 relative to each other beyond that swinging movement necessary to expand these sections to produce the annulus 15. The opposite edges of each of the groups of sections 17 from those edges thereof which are connected to the base section 16, are

connected together by an external hinge 22, pin 23 of which is bent rearwardly and into an eye to form an operating handle 24.

Extending outwardly from the sections 16 are 5 bag holding means such as pins 25.

Operation

The bag holder 10 of my invention is adapted to be manually operated, the first step being to collapse the annulus 15 by pushing inwardly on the handle 24, this extreme collapsed position being shown by dotted lines 30 in Fig. 2. The mouth of the empty bag is now pulled over the bead 20 and then lifted above the level of the bottom of the annulus 15 while the handle 24 is pulled outwardly to expand the annulus when in the mouth of the bag as shown in Figs. 1 and 3. To accomplish this the sections 17 successively pass from the position 30 to the positions shown by broken lines 31 and that shown by the broken lines 32 (see Fig. 2). In order to complete the expansion of the annulus 15 from the position shown by broken lines 32 to the position shown in full lines in Fig. 2, the base section 16 must be sprung slightly as indicated by broken lines 33 in Fig. 2. The reason for assembling the bag holder 10 in this manner is so that when the annulus 15 is completely expanded it will tend to remain in an expanded condition and will effectively resist forces tending to collapse this while the bag is being filled.

When the annulus 15 is expanded in order to support the mouth of the bag B for filling the latter, the pins 25 extend through or into the material of the bag B and cooperate with the bead 20 to positively prevent the bag coming off the bag holder 10 while the annulus 15 is expanded.

After a bag B has been applied to the bag holder 10 as above described, material is delivered through the annulus 15 into this bag. When the desired amount of material has thus been delivered into the bag, the handle 24 is pushed inwardly to fully collapse the annulus 15 as indicated by broken lines 30 of Fig. 2. This withdraws the pins 25 from the bag and allows the rear portion of the mouth of the bag to fall away from over the bead 20 so that the filled bag may readily be shifted away from under the bag holder 10.

A bag B thus having been applied to the bag holder 10 and filled and removed, the bag holder is in readiness for a repetition of this procedure 55 by virtue of the fact that the annulus 15 is now

collapsed as indicated by the broken lines 30 in Figs. 1 and 2.

I claim:

1. A bag holder comprising: an annulus adapted to extend into and be expanded in the mouth of a bag, said annulus being formed of at least three sections hinged together at their respective contiguous ends on axes parallel with the axis of the annulus, certain of said sections being collapsible inwardly by pivoting said sections relative to each other about said hinge axis to disengage said holder from a bag.

2. A bag holder comprising: an annulus adapted to extend into and be expanded in the mouth of a bag; bag engaging means on the outer surface of said annulus for retaining said bag on said annulus when the latter is expanded in said mouth, said annulus being formed of at least three sections; means for hingedly uniting all of said sections at their respective contiguous ends on axes parallel with the axis of said annulus to permit certain of said hinged sections to be swung inwardly by pivoting said sections relative to each other about said hinge axes to release said bag from said bag holder.

3. A bag holder comprising: a series of at least three sections with their respective contiguous ends hingedly connected together on vertical axes to form an annulus adapted to extend into and be expanded in the mouth of a bag, one of said sections being larger than the other; and mounting means connected to said larger section in order to support said annulus, said other sections being adapted to collapse in the plane of said annulus by said sections pivoting relative to each other about said hinge axes and extend into the space within said larger section to release a bag from around said annulus.

4. A bag holder comprising: a substantially semi-cylindrical base section; a plurality of auxiliary sections hingedly connected to each other and to said base section at their respective contiguous ends on spaced vertical axes to form an annulus when expanded, said annulus being adapted when collapsed to extend into the mouth of a bag and then be expanded; and means on the outer surfaces of said sections for engaging the mouth of the bag when said annulus is expanded therein to hold said mouth in place and to support said bag on said annulus, said bag being released from said holding means when said auxiliary sections are collapsed inwardly.

5. A bag holder comprising: a plurality of at least three sections all of which are pivotally connected together at their contiguous ends to form a collapsible annulus with an axis parallel with the axes of said pivotal connections, said annulus being adapted when collapsed to be inserted in the mouth of a bag and to be expanded therein to engage and support said bag; and manual means for collapsing certain of said sections inwardly to release a bag from said annulus.

6. A bag holder comprising: a substantially semi-circular section; a plurality of auxiliary sections pivotally connected to each other and to said semi-circular section to form an annulus, the axis of which is substantially parallel with the axes of said pivotal connections, one of said pivotal connections being adapted to break in-

wardly, the balance of said pivotal connections being adapted to break outwardly.

7. A bag holder comprising: a substantially semi-circular section; four auxiliary sections pivotally connected to each other and to said semi-circular section to form an annulus, the axis of which is substantially parallel with the axes of said pivotal connections, one of said pivotal connections being adapted to break inwardly, 10 the balance of said pivotal connections being adapted to break outwardly; and handle means connected to said pivotal connection which breaks inwardly for collapsing or expanding said annulus.

15 8. A bag holder comprising: a semi-circular section; means for supporting said section; a bead formed outwardly about the lower edge of said section; a plurality of auxiliary sections pivotally connected to each other and to said base section to form an annulus the axis of which is substantially parallel with the axes of said pivotal connections, said auxiliary sections being adapted to be expanded, while the mouth of a bag is placed around said sections, to form said annulus in the mouth of said bag to substantially fit said mouth; and means on said auxiliary sections for extending outwardly into said bag to cooperate with said bead on said base section to suspend said bag from said holder while said sections are so expanded, said auxiliary sections being collapsible and swinging about the pivots of their interconnecting hinges to release said bag from said holding means and permit said bag to slip downwardly from said bag holder.

9. A bag holder comprising: an annulus including a base section, two groups of auxiliary sections, internal hinges connecting together the sections of each such group and connecting one end of each of said groups to one end of said base section; an external hinge connecting the other ends of said groups, said hinges being so applied that when the joints formed thereby are flexed to expand said sections to form said annulus, the springing of at least one of said sections is requisite; and means on said annulus facing outwardly to engage a bag the mouth of which is placed upwardly over said section to retain said bag suspended on said annulus when the latter is formed by expanding said sections within the mouth of said bag.

10. A bag holder comprising: an annulus including a base section, two groups of auxiliary sections, internal hinges connecting together the sections of each such group and connecting one end of each of said groups to one end of said base section and an external hinge connecting the other ends of said groups, said hinges being so applied that when the joints formed thereby are flexed to expand said sections to form said annulus, the springing of at least one of said sections is requisite; means on said annulus facing outwardly to engage a bag the mouth of which is placed upwardly over said annulus to retain said bag suspended on said annulus when the latter is expanded within the mouth of said bag; and a handle on said external hinge by which said annulus may be collapsed or expanded at will.

JOHN C. BROOME.
